WALL TILE

Anthony J. Izewski, Franklin Park, Ill.

Application October 21, 1955, Serial No. 38,507

Term of patent 14 years

(Cl. D18—2)

Fig. 1.

Fig. 2.

Fig. 3.

Fig. 4.

Fig. 1 is a front elevational view of a wall tile showing my new design;

Fig. 2 is a rear elevational view thereof;

Fig. 3 is a top plan view thereof; and

Fig. 4 is a horizontal sectional view thereof taken substantially along the line 4—4 of Fig. 1.

The dominant features of my design reside in the portions shown in full lines.

I claim:

The ornamental design for wall tile, as shown and described.
